DOWNSPOUT OF WOOD FOR GUTTERS

Neal T. MacKenzie, St. Paul, Minn., assignor to
General Timber Service, Inc., St. Paul, Minn.,
a corporation of Delaware

Application October 8, 1942, Serial No. 461,243

4 Claims. (Cl. 138—28)

Heretofore downspouts constructed from wood have been subject to the objection that they are insufficiently elastic and strong to withstand freezing conditions when they become filled with ice due to a stoppage or to the gradual accumulation of ice on the interior surfaces.

The principal object of the present invention is to provide a novel conduit of this class which is protected against the breakage resulting from such accumulations of ice by the provision of compressible means extending parallel to the water passage and so located as to compensate for the expansion of ice in the water passage.

Other objects will appear and be more fully pointed out in the following specification and claims.

Referring to the accompanying drawing:

Figure 1 is a cross section through a wood gutter and showing adjacent members of a building and my improved downspout partially in elevation and partially in central, longitudinal section, taken on the line 1—1 of Fig. 2;

Fig. 2 is a section taken on the line 2—2 of Fig. 1, and with a portion of the front wall of the downspout removed;

Fig. 3 is a typical horizontal section through my improved downspout;

Fig. 4 is a longitudinal section through a short, straight length of the spout which may be readily cut in the field as an insert to provide for installations where the eaves overhang various distances relative to the walls of the building or for other purpose, and

Fig. 5 is a cross-sectional view showing an alternate type of compressible means for relieving pressure on the outer walls when the contents of the water passage freezes.

As shown in Figs. 1 and 2, a gutter 5 of wood and of standard shape is mounted on a building having roof sheathing 6 and wall sheathing 7. My improved downspout comprises elbow members 8 and 9 and a straight member 10 adapted to fit together end to end with telescope type end joints. Each of these members is composed of longitudinally extending, outer wall pieces 11, 12, 13 and 14 forming a substantially rectangular conduit and connected together with rabbeted joints 15 which may be fastened by waterproof adhesive or by nails or both adhesive and nails or by other suitable means. Within the conduit, water passages 16 are separated from each other by flexible diaphragms 17 and an intervening air space 18 extending longitudinally of the water passages, the diaphragms being fas-

tened in parallel grooves 19 by a waterproof and elastic adhesive or matrix.

The wall pieces and diaphragms are preferably constructed from cedar or redwood and the diaphragms may be made approximately $\frac{1}{8}$ of an inch in thickness while the wall pieces are relatively rigid and thick being, preferably, shaped from stock of approximately one inch thickness. Water is excluded from the air space 18 by closing the latter at the upper end of each member 8, 9 and 10 by means of short plugs 20. The lower end of the air space in each member is left open. As shown, the elbow members 8 and 9 form a goose neck pipe bend, each of these members making a 45 degree angle bend. The pieces 11 and 12 of these members are preferably steam treated to facilitate bending and are thereafter held in suitable jigs or forms until set in the required shape or they may be shaped from solid blocks.

It will be understood that the grain of the wood extends approximately longitudinally of the spout in all of the pieces 11, 12, 13 and 14 as well as in the diaphragms 17, and all of these pieces are preferably impregnated with a suitable waterproofing composition.

As shown in Fig. 4, a short, straight member 21 of the spout is provided for use at the joint 22 between the members 8 and 9. This is required where the gutter 5 is offset from the wall 7 a greater distance than can be spanned by the two elbow members 8 and 9. The female end surfaces 23 of the member 21 are formed at the factory but this member is cut to the required length and its male joint surfaces should be formed in the field by a carpenter. This cutting of the male end joint is facilitated by my provision of guide shoulders 24 (Fig. 3) on the exterior of the conduit which also improve its appearance. The carpenter saw cuts in from the end in planes 25 extending parallel to the axis of the conduit, these planes being located with the shoulders 24 as a guide. Either before or after this operation, the upper end of the male joint projection is formed by cutting the required depth from the exterior of the member 21 in a plane 26 (Fig. 4) which is perpendicular to the axis of the conduit and located by measurement of the length of member 21 that is required for the particular job. This shapes the lower end of the member 21 so that it fits accurately into the upper end of the member 9 and the resulting insert is used between the elbow members to adapt the spout for a particular building. By similar cutting of other short spout members

other adjustments of the total length may be made in situ. The several joints between the gutter and member 8 and between the members 8, 9, 10 and 21 may be fastened by the use of small nails driven into the telescoping ends of the members or by use of waterproof adhesive or otherwise.

In operation, water flows from the gutter 5 into the main downspout passages 16 and is conducted thereby to a place of disposal, being excluded from the air spaces 18 between the diaphragms 17 by the plugs 20. Upon the freezing of water in the passages 16, the diaphragms 17 allow for the resulting expansion of the ice by merely expanding into the air space 18 without rupturing. They thus relieve the outer wall members of the excessive internal pressure which might otherwise be produced by the freezing.

As shown in Fig. 5, a body of compressible material 27 may be substituted for the flexible diaphragms 17. This body extends longitudinally of the water passages 16, between them, and is adapted to relieve pressure on the outer walls of the conduit when water freezes in the passages 16. The edges of the material 27 are preferably confined in grooves formed in the members 11 and 12 and this material is sufficiently resilient to return to its normal shape when the pressure thereon is relieved. Sponge rubber may be used as the material 27 when available, otherwise a highly porous and flexible fibrous or sponge material enclosed in an impervious coating 28 may be employed as the compressible means extending along the water passages. A permanently flexible asphaltic coating or other waterproof compositions having similar properties may be used as the coating 28.

Ordinarily accumulations of ice progressively increase in thickness from the inner surfaces of the pieces 13 and 14 and adjacent margins of the pieces 11 and 12 toward the longitudinal center plane of the conduit along which the air space 18 or compressible material 27 extend. As shown in Figs. 3 and 5, the passages 16 are approximately oval shape in cross section and the air space 18 and compressible material 27 extend across the longer axes of the ovals at the adjoining ends thereof. By so forming the passages and arranging the compressible means I direct the forces of expansion toward the longi-

tudinal center plane and thereby increase the effectiveness of my device in relieving pressure on the outer wall members.

Having described my invention, what I claim as new and desire to protect by Letters Patent is:

1. A downspout comprising substantially rigid, inflexible outer wall members forming a conduit for water, a plurality of relatively flexible diaphragms extending longitudinally within said conduit and dividing the interior thereof into a plurality of water passages and an intervening air space, the longitudinal edges of said diaphragms fitting in grooves formed in opposite outer wall members and means for excluding water from said air space, said diaphragms being extensible into said air space under the increased pressure resulting from the freezing of water in said passages.

2. A downspout comprising substantially rigid, inflexible outer wall members formed from wood and a plurality of relatively thin, flexible and elastic members extending longitudinally within said conduit in spaced relation to each other, said members being compressible toward each other under the increased pressure resulting from the freezing of water in said passages.

3. A conduit comprising, outer wall members of rigid inflexible material forming a hollow structure and a compressible partition dividing the conduit longitudinally into separate passages for liquid and extending completely across a side of each of said passages in contact with opposite outer wall members, said partition being sufficiently compressible to relieve pressure on said outer wall members resulting from the freezing of the liquid in said passages.

4. A conduit comprising, outer side and end wall members of wood forming a hollow structure of substantially oblong shape in cross section and a compressible partition extending parallel to the end wall members and completely across the conduit to divide it longitudinally into separate passages for liquid, said partition being sufficiently compressible to relieve pressure on said outer wall members resulting from freezing of the liquid in said passages and the longitudinal edges of said partition extending in contact with the outer side wall members.
